ORNAMENT AND BUTTON SHIELD

Abraham Jacobs, Cleveland, Ohio

Application December 22, 1937, Serial No. 181,155

7 Claims. (Cl. 68—235)

This invention relates to shields and particularly to those protective devices used to cover buttons, ornaments and similar articles attached to clothing and which cannot be conveniently removed for cleaning or laundering of the garment.

One of the objects of the invention is to provide an article, which will prevent non-textile ornaments, buttons or delicate decorations, which are attached to women's clothing, from being damaged or from damaging other material during the agitation of a cleaning or a laundering process.

Another object of the invention is to eliminate the necessity of having to detach buttons and the like from textile articles about to be cleaned and of having to re-attach them afterwards.

A further object is to utilize a synthetic rubber or similar material for the structure of the article and which material is capable of withstanding the chemical re-action of the fluids now used in commercial dry cleaning processes.

A still further object is to provide a device of the class mentioned, which is inexpensive to manufacture; is easy and simple to use; and which, through the use of a set of two universal styles, can accommodate practically all sizes, shapes and materials of buttons, buckles, clasps and ornaments ordinarily attached to women's clothing.

These and other features of this invention are more fully set forth hereinafter, reference being made to the accompanying drawings, in which like parts are designated by like reference characters, and in which:

Figure 1 is a front elevation of the shield covering a button attached to a piece of textile fabric;

Figure 2 is a side elevation of the same shield;

Figure 3 is a half section of the same shield, the view taken along the lines 3—3 of Figure 1;

Figure 4 is a rear view of the same shield enclosing a button, the view taken in the direction of the arrows of line 4—4 of Figure 2;

Figure 5 is a side view of the shield partly opened and admitting a button for protection;

Figure 6 is a rear view of the same shield taken along the lines 6—6 of Figure 5;

Figure 7 is a front elevation of a modified form of shield;

Figure 8 is a half sectional view of the modified form of shield attached to a round button, the view taken along the lines 8—8 of Figure 7;

Figure 9 is a sectional view of the modified shield, partly off of a round button;

Figure 10 is a side sectional view of the modi-

fied style of shield completely assembled to protect an irregular shaped button;

Figure 11 is an exploded view, in section, of the modified style of shield, similar to Figure 10; and

Figure 12 is a rear view of the modified style of shield.

Conducive to a clearer understanding of this invention, it may be well at the outset, to point out that in the dry cleaning business, it is necessary to remove all buttons, metallic or glass ornaments and the like from women's garments before immersing the garment in the cleaning fluid and subsequently to sew on or otherwise attach the removed buttons or ornaments. This is necessary because the sharp edges of metallic or glass ornaments might cut the material of the garment; the heavier objects might tear loose and destroy the textile; and delicate glass buttons might be broken in the somewhat violent agitation of the cleaning process.

The removal and subsequent attachment of the buttons is not only time consuming and expensive, but causes a weakening of the textile fabric and also, causes trouble, inconvenience and sometimes considerable financial loss, if a removed button becomes lost or broken and cannot be replaced. This is especially true in cleaning women's delicate silk outer garments.

To overcome the foregoing obstacles, I provide a flexible and somewhat elastic shield made of synthetic rubber or similar material, or made of a recently patented material known commercially as Neoprene. The texture, flexibility and elasticity of the material is somewhat like that of an ordinary rubber pencil eraser, and is so treated, that it is not easily effected by gasoline solvents, the most commonly used fluid in commercial cleaning.

To accommodate the large variety of sizes and shapes of buttons and ornaments, three types of shields are herein described.

The first type, which is illustrated in the Figures 1, 2, 3, 4, 5 and 6, consists of a body member 21 of any suitable shape or size. The preferred shape however, being that of a circular cup. To its rim 22, there is attached a curtain or web 23. This web 23, referred to in the claims as the side portion, is somewhat flexible and is quite resilient. Further, this web 23, is made of a comparatively thin material, has spiraliform plait 24, which normally close the opening of the body member 21 as shown in the Figures 2, 3 and 4. Twisting the web 23, in the direction opposite to the general direction of the plait 24, will cause the plait 24 to unfold, spread apart and become erect. This

also enlarges the opening 25 so that a buckle, clasp, ornament or button 26 may be inserted for cover and protection. The Figures 5 and 6 show how the web 23 can be expanded and stretched 5 for the insertion of the button 26.

The body member 21 has a plurality of openings or vents 28, which permit the cleaning fluid to flow in and to circulate around the button. These vents 28 are particularly desirable when 10 the buttons are cloth covered and which also need cleaning.

The body member wall 29, is light in weight, soft and pliable. It is reinforced near the rim 22, and at the center. The reinforcement 31 near the rim 22, helps keep its shape and furnishes a base to which the web 23 can be attached. The reinforcement 32 in the center acts as a cushion or bumper for the button 26.

To remove this shield, the operator need only to 20 grasp the fabric with one hand at the point where the button is attached to it, and with the other hand, twist and pull the body member until the enclosed button snaps out.

For the sake of simplicity the Figures 1 to 6 25 show an irregular shaped button; Figures 7 to 9 show a round button, and Figures 10 to 12 show another irregular shaped button; but it is apparent that many other shapes, sizes and materials can be likewise accommodated.

30 The second type of shield, which is illustrated in the Figures 7, 8, 9, 10, 11 and 12 is very similar to the first type of shield heretofore described. It consists of a body or base member 41, having a rim 42, vents 48, a reinforcement 51 near the rim 42 and a reinforcement 52 at its center. In addition, the base member 41 has at 35 the reinforcement 51 and close to the rim 42, an external circumferential bead 43 and two inner circumferential ribs 44, which form an annular groove 45 just inside the rim 42. The external circumferential bead 43 increases the resiliency of 40 the rim 42 and assists the interior annular ribs 44 or the groove 45 to better cover and retain the article to be protected.

45 A cap member 46 is provided to cover the base member 41 if necessary. The cap member 46 is slightly larger than the base member 41, but has similar vents 49 and rim and center reinforcements 50 and 53 respectively. This cap member 50 has also an inner circumferential flange 57, which snaps over the bead 43.

If the button 54 which is to be protected, is 55 round and of a standard size, it can be protected by the base member 41 alone, as illustrated in the Figures 7, 8 and 9. All that is then required, is to fit the edge of the round button 54 in the groove 45. The resiliency of the base member material being sufficient to hold it on and to protect the button. A slight pressure against the 60 hollow sides of the base member 41, will flare the rim 42, so that it can be attached or detached with relative ease and speed.

If the clasp, ornament or button 54a, is irregular in shape and not able to be grasped by the 65 internal ribs 44, the button 54a is nevertheless inserted in the base member 41 and the cap member 46 is applied over and around the rim and onto the bead 43, with the textile fabric 55

in between the bead 43 and the flange 47, as shown in the Figures 10, 11 and 12.

In using the base member 41 and the cap member 46, the material 55 near the button 54a will become wrinkled, but no damage will be done to the fabric, and the material will not be weakened by cutting off and then subsequently sewing on the button.

While I have illustrated in the drawings the preferred forms of the invention, it is to be understood that there are other forms which will suggest themselves to persons skilled in the cleaning and laundering art, and those modifications as well as modifications of the illustrated forms are all considered to be within the broad 15 scope of the invention, as it is to be understood that no limitations are intended except those imposed by the appended claims.

Having thus described my invention I now 20 claim:

1. A shield formed of a cup-shaped body member made of a flexible material having a vent, its side portion being resilient and having means for retaining an article to be protected.

2. A shield formed of a cup-shaped body member having a concave base portion made of a flexible inelastic material, having a vent, and a side portion extending from the edge of the base portion made of flexible elastic material having a plaited web entwining within the said body 30 member an article to be protected.

3. A shield comprising, a cup-shaped body member having a vent, the said body member also having bumpers, a spiraliform plaited cover member attached to the said body member for entwining within the two members an article to be 35 protected.

4. A shield comprising, a cup-shaped body member having a vent therein, a plaited cover member attached to the said body member for enclosing within the two members an article to be 40 protected.

5. A shield comprising, a concave body member having a vent, an interior circumferential groove enclosing an article to be protected, an 45 exterior circumferential bead contiguous to the said groove; a cap member having vents, and an interior circumferential flange engaging the said bead.

6. A shield comprising, a cup-shaped body 50 member having a vent; the said body member also having interior annular ribs enclosing an article to be protected, exterior bumpers for absorbing shock to the said article, an exterior annular bead contiguous to the said annular ribs; and a cap 55 member having a vent, the said cap member having an interior annular flange for engaging the exterior annular bead of the said body member.

7. A shield comprising a resilient cup-shaped 60 body member having a vent, the said body member having spaced interior annular ribs for retaining an article to be protected, exterior bumpers for absorbing shock to the said article, and an exterior annular bead contiguous to the 65 said annular ribs to stiffen same.

ABRAHAM JACOBS.
